LIQUID APPLICATOR

Miles E. Landau, Brooklyn, N. Y.

Application September 11, 1944, Serial No. 553,565

8 Claims. (Cl. 91—54.4)

1

This invention relates to liquid applicators of the type adapted for moistening gummed surfaces and for wetting the fingers so as to facilitate the handling or counting of currency and the like and while not limited thereto the present invention is directed to a liquid applicator which is so constructed as to automatically dispense the liquid as the same is required and to maintain the applicator surface in a moistened condition.

The invention has in view an applicator of the indicated character having a liquid reservoir which is sealed against the intake of air and the discharge of the liquid except through an orifice located adjacent the bottom thereof and which orifice is covered by a cellular sponge functioning when the same is saturated to limit the discharge of the liquid to the amount required or removed from the sponge.

The invention further comprehends a liquid applicator provided with a pair of cellular sponges disposed in superimposed relation and so located that the lower sponge covers the orifice of the liquid reservoir and restricts the flow of the liquid therethrough to the volume of air admitted to the reservoir through the interstices in the lower sponge by the absorption of the liquid from the lower sponge by the upper sponge.

The invention also resides in improved means for resiliently supporting the liquid reservoir in a socket in juxtaposition to the sponges whereby the reservoir may be readily removed for refilling and replaced with the orifice thereof disposed in alignment with a discharge opening in the socket and whereby the reservoir is snugly compressed against the wall of the socket adjacent said discharge opening to thereby permit the discharge of the liquid through said opening and into the lower sponge.

With the foregoing and other objects in view, reference is now made to the following specification and accompanying drawings in which are illustrated the preferred embodiments of the invention.

In the drawings:

Fig. 1 is a perspective view of a liquid applicator constructed in accordance with the invention.

Fig. 2 is a longitudinal sectional view taken on a vertical plane.

Fig. 3 is a fragmentary horizontal sectional view taken on the line 3—3 of Fig. 2.

Fig. 4 is a perspective view of the liquid reservoir.

Fig. 5 is a similar view of the socket.

2

Fig. 6 is a perspective view of a modified form of the invention.

Fig. 7 is a vertical sectional view therethrough.

Fig. 8 is a perspective view of a liquid applicator illustrating another modification of the invention.

Fig. 9 is a fragmentary vertical sectional view therethrough.

Referring to the drawings by characters of reference and more particularly to the form of the invention illustrated in Figures 1 to 5 thereof, the applicator includes a base or holder 10 of general rectangular formation having a cylindrical shaped well 11 opening through the upper surface thereof and which well communicates with a rectangular shaped recess 12 located forwardly thereof and extending inwardly from the upper face of the base or holder 10.

The wall of the well 11 is threaded as at 13 adjacent the bottom thereof for removably receiving a cylindrical sleeve 14 exteriorly threaded as at 15 adjacent the lower end thereof and which is of a length to project upwardly through the well with the upper end thereof disposed slightly above the upper face of the base or holder 10. The said sleeve is provided with an aperture 16 located above the threaded portion 15 and arranged when the sleeve is secured in the well to open into the rectangular shaped recess 12. Opposite the aperture 16, the sleeve 14 is formed with a slit 17 extending longitudinally thereof from the upper edge to a transversely disposed slit 18 located adjacent the threaded portion 15 and extending forwardly a short distance at each side of the slit 17 to thereby form oppositely disposed resilient arcuate members 19 and 20 at the rear of the sleeve. The sleeve provides a socket for slidably receiving and supporting a container 21 in the base or holder 10 in juxtaposition to the rectangular recess 12 which container 21 constitutes a reservoir for holding a supply of the liquid to be dispensed by the applicator.

The container 21 may be of any desired formation and which as illustrated consists of a spherical shaped hollow body 22 having a depending cylindrical shank 23 provided with an orifice 24 located adjacent the bottom thereof and which orifice is slightly larger than the aperture 16 and is disposed in registry therewith when the container is positioned in the sleeve. The resilient arcuate members 19 and 20 of the sleeve function to frictionally secure the container 21 in the sleeve and to compress the shank 23 thereof against the wall 55 of the sleeve in the region of the aperture 16 so

as to insure the discharge of the liquid through the aperture 16.

The shank 23 is formed with a projection 25 extending outwardly at the side thereof opposite the orifice 24 and which projection is of a size to slidably engage in the slit 17 between the ends of the resilient arcuate members 19 and 20 for disposing and retaining the container in position in the sleeve with the orifice 24 thereof arranged in registry with the aperture 16.

The applicator also includes superimposed upper and lower rectangular shaped sponges 26 and 27 which fit into the rectangular shaped recess 12 with the upper sponge protruding slightly above the rim of the recess and with the lower sponge disposed with the inner end thereof abutting against the sleeve 14 so as to cover the aperture 16. Preferably the sponges 26 and 27 are of a fine pore synthetic material such as cellulose or any equivalent thereof and due to the arrangement thereof function to supply the required amount of the liquid to the upper sponge so as to maintain the same in a moistened condition while eliminating excess liquid in the recess 12. This is accomplished by the lower sponge 27 functioning when the same is saturated with the liquid to prevent the entrance of air into the container 21 except such as admitted thereto by the taking up of the liquid from the lower sponge through the medium of the absorptive action of the upper sponge, thus limiting the discharge of the liquid from the container 21 to the amount required to maintain the applicator surface of the upper sponge in a moistened condition. The arrangement of the sponges also renders it possible to conveniently remove the upper sponge for cleaning the accumulation of gummy material which adheres thereto when moistening envelopes and the like without disturbing the lower sponge.

In the form of the invention illustrated in Figures 6 and 7 of the drawings, the base or holder 30 of the applicator is of circular formation having a circular recess 31 in the upper face thereof and centrally of the recess the bottom thereof is formed with a circular well 32 adapted to threadedly receive therein an upstanding sleeve 33 having an aperture 34 and which sleeve is similar to and functions in the same manner as the sleeve 14 in the previous form of the invention. The sleeve 33 projects upwardly above the rim of the base or holder 30 and is adapted to frictionally receive and support a container 35 having an orifice 36 adjacent the bottom thereof providing a discharge outlet, the container 35 constituting a liquid reservoir and being similar in construction to the container 21 in the previous form of the invention.

Superimposed upper and lower centrally apertured sponges 37 and 38 are provided which are arranged in the circular recess 31 in surrounding relation with the sleeve 33 and with the upper sponge 37 protruding above the rim of the base or holder 30. The inner periphery of the lower sponge 38 snugly fits about the sleeve 33 and covers the aperture 34 therein so as to effect the discharge of the liquid from the reservoir. A thin centrally apertured flexible disk 39 of waterproof material is provided which is arranged upon the upper sponge 37 with the central aperture thereof disposed about the sleeve 33. Above the sponge 37 the disk 39 is provided with closely spaced perforations 40 through which the liquid from the upper sponge 37 is exuded or expressed by slight pressure or tapping on the upper surface of the disk 39. The outer periphery of the lower sponge

38 is preferably spaced from the wall of the recess 31 as shown in Fig. 7 forming an annular space in which the liquid forced from the sponges by pressure thereagainst will collect so as to avoid the recess 21 filling up and the liquid spilling over the edges thereof.

In the form of the invention illustrated in Figures 8 and 9 of the drawings, the applicator is similar in construction to the form shown in Figures 1 to 5 thereof except that in this form a container 42 is provided which is of cylindrical formation and furnishes a relatively larger liquid reservoir. The container 42 is slidably mounted in a sleeve 43 frictionally fitted in a circular recess 44 in the base or holder 45 which recess communicates with a rectangular shaped recess 46 in the forward portion of the base or holder. The container 42 is provided with an orifice 47 disposed in registry with an aperture 48 in the sleeve 43 which functions as in the previous forms of the invention to discharge the liquid to the upper and lower sponges 49 and 50 disposed in the recess 46 with the rear end of the lower sponge 50 arranged in abutting relation over the aperture 48. The sleeve 43 is slit as at 51 for frictionally gripping the container which is formed with a projection 52 adapted to engage in the slit 51 for automatically positioning the container with the orifice 47 thereof in registry with the aperture 48.

It is to be understood that the container or liquid reservoir in each form of the invention being closed at the top and the orifice thereof being relatively small, the liquid will not run out or be discharged therefrom except by the capillary action of the lower sponge. For this reason the lower sponge is positioned in covering relation with the aperture in the sleeve and in contact with a globule of the liquid which protrudes from the orifice in the container or liquid reservoir whereby the sponge sets up a suctional action on the liquid in the container or reservoir to draw the same therefrom as required to maintain the upper sponge in a moistened condition.

To fill the container or reservoir the same is removed from the applicator and held with the orifice thereof disposed under a stream of the liquid such as a running faucet, the weight and velocity of the falling liquid being such as to force the same into the orifice thereof and displacing the air in the container. Prior to the first use thereof the sponges are removed and saturated or filled with the liquid. Preferably the container or reservoir is constructed of transparent or translucent material so that the height of the liquid therein is apparent at all times.

What is claimed is:

1. In a liquid applicator, a container defining a liquid reservoir having a closed upper end and an outlet adjacent the lower end thereof, a holder, a socket member mounted in said holder for slidably receiving and supporting the liquid reservoir, said socket member having an opening at one side thereof and a pair of resilient clamping members adapted to resiliently compress the reservoir against the wall of the socket member in the region of the said opening with the outlet thereof in registry with said opening, and a pair of superimposed sponges disposed in said holder with the lower sponge arranged in covering relation with the opening in said socket member to control the flow of the liquid from the reservoir when the lower sponge is saturated.
2. In a liquid applicator, a container defining

a liquid reservoir having a closed upper end and a cylindrical lower portion provided with an outlet adjacent the bottom thereof, a holder, a socket member mounted in said holder and having an opening at one side thereof and a vertically split upper portion defining a pair of resilient arcuate clamping tongues spaced apart at their ends and adapted to receive the cylindrical lower portion of the reservoir for supporting the same and functioning to resiliently compress the lower portion of the reservoir against the wall of the socket member in the region of said opening therein, means carried by the cylindrical portion of said reservoir engageable between the ends of the clamping tongues for disposing and maintaining the reservoir with the outlet thereof in registry with the opening in the socket member and a pair of superimposed cellulose sponges disposed in said holder with the lower sponge arranged in covering relation with the opening in said socket member to control the flow of the liquid from the reservoir when the lower sponge is saturated.

3. In a liquid applicator, a container defining a liquid reservoir having a closed upper end and an outlet adjacent the lower end thereof, a holder, means mounting said reservoir in said holder and having an opening registering with the outlet in the liquid reservoir, and a pair of superimposed sponges disposed in said holder with the lower sponge arranged in covering relation with said outlet and functioning when the lower sponge is saturated to effect the discharge of the liquid from the reservoir to the amount taken up by the upper sponge.

4. In a liquid applicator, a container defining a liquid reservoir having a discharge outlet adjacent the lower end thereof, a holder, a tubular sleeve having a threaded lower end portion threadedly secured in said holder and adapted to slidably receive and support the liquid reservoir, said sleeve having an opening therein and a split upper portion defining a pair of resilient clamping members adapted to resiliently compress the reservoir against the wall of the sleeve in the region of the outlet and with said opening registering with the discharge outlet, a pair of superimposed sponges disposed in said holder with the lower sponge arranged in covering relation with the discharge opening, and a plate having an opening therein through which the reservoir projects and having a foraminous portion overlying said upper sponge adapted for moistening the fingers through the openings in the foraminous portion.

5. In a liquid applicator, a container defining a liquid reservoir having an outlet adjacent the lower end thereof, a holder having a circular recess opening through the upper face thereof and a rectangular recess communicating with said circular recess and extending inwardly from the upper surface of said holder, a socket member threadedly secured in said circular recess and

having an opening at one side thereof and directed into said rectangular recess, said socket member being adapted to receive and support the container in the holder with the outlet thereof in registry with the opening in the socket member, and a sponge disposed in said rectangular recess with one side thereof abutting against the socket member so as to cover the opening therein to thereby effect the discharge of the liquid from the container.

6. In a liquid applicator, a container defining a liquid reservoir having an orifice in the lower portion thereof, a holder, a tubular sleeve secured in said holder and having an opening and resilient clamping means adapted to receive and resiliently retain the reservoir in the sleeve with said opening registering with the orifice, a pair of superimposed sponges disposed in said holder with the lower sponge arranged in covering relation with the orifice in the reservoir and a shield having a foraminous portion overlying said upper sponge and adapted to admit liquid from the upper sponge therethrough.

7. In a liquid applicator, a container defining a liquid reservoir having a closed upper end and an outlet adjacent the lower end thereof, a holder, a socket member mounted in said holder for slidably receiving and supporting the liquid reservoir, said socket member having an opening at one side thereof and a pair of resilient clamping members adapted to resiliently compress the reservoir against the wall of the socket member in the region of the said opening with the outlet thereof in registry with said opening, and a sponge disposed in said holder in covering relation with the opening in said socket member to control the flow of the liquid from the reservoir.

8. In a liquid applicator, a holder, a liquid container defining a liquid reservoir having a closed upper end and an orifice in the lower portion thereof, a socket member disposed in said holder, said socket member receiving said reservoir and having an orifice in registry with the orifice in said reservoir to permit the passage of liquid therethrough, and sponge material disposed in said holder in covering relation with said orifice in the socket member to effect and control the discharge of liquid from said reservoir.
